(57) **CLAIM**

The ornamental design for a shipping base as shown and described.

DESCRIPTION

FIG. 1 is a top perspective view of a shipping base showing the first embodiment of our new design;
FIG. 2 is a bottom perspective view thereof;

FIG. 3 is a left side elevational view, the right side being a mirror image thereof;

FIG. 4 is a front side elevational view, the back side being a mirror image thereof;

FIG. 5 is a top plan view thereof;

FIG. 6 is a bottom plan view thereof;

FIG. 7 is an enlarged detail view taken from line 7 in FIG. 1;

FIG. 8 is an enlarged detail view taken from line 8 in FIG. 1;

FIG. 9 is an enlarged detail view taken from line 9 in FIG. 2;

FIG. 10 is an enlarged detail view taken from line 10 in FIG. 2;

FIG. 11 is a top perspective view of a shipping base showing the second embodiment of our new design;

FIG. 12 is a bottom perspective view thereof;

FIG. 13 is a front side elevational view, the back side being a mirror image thereof;

FIG. 14 is a left side elevational view, the right side being a mirror image thereof;

FIG. 15 is a top plan view thereof;

FIG. 16 is a bottom plan view thereof;

FIG. 17 is an enlarged detail view taken from line 17 in FIG. 11;

FIG. 18 is an enlarged detail view taken from line 18 in FIG. 11;

FIG. 19 is an enlarged detail view taken from line 19 in FIG. 12;

FIG. 20 is an enlarged detail view taken from line 20 in FIG. 12;

FIG. 21 is a top perspective view of a shipping base showing the third embodiment of our new design;

FIG. 22 is a bottom perspective view thereof;

FIG. 23 is a front side elevational view, the back side being a mirror image thereof;

FIG. 24 is a left side elevational view, the right side being a mirror image thereof;

FIG. 25 is a top plan view thereof;

FIG. 26 is a bottom plan view thereof;

FIG. 27 is an enlarged detail view taken from line 27 in FIG. 21;

FIG. 28 is an enlarged detail view taken from line 28 in FIG. 21;

(Continued)

FIG. 29 is an enlarged detail view taken from line 29 in FIG. 21;

FIG. 30 is an enlarged detail view taken from line 30 in FIG. 22;

FIG. 31 is an enlarged detail view taken from line 31 in FIG. 22; and,

FIG. 32 is an enlarged detail view taken from line 32 in FIG. 22.

The broken lines in the figures depict portions of the shipping base that form no part of the claimed design. The broken line boxes in FIGS. 1, 2, 7-12, 17-22, and 27-32 are for the purpose of annotating enlarged portions that form no part of the claimed design.

1 Claim, 28 Drawing Sheets
